BY
Watson E. Coleman
ATTORNEY.

UNITED STATES PATENT OFFICE.

JOHN G. LUCAS, OF DEARBORN, MICHIGAN.

SIGNAL-INDICATOR FOR AUTOMOBILES.

1,385,016.

Specification of Letters Patent. Patented July 19, 1921.

Application filed October 6, 1920. Serial No. 414,979.

To all whom it may concern:

Be it known that I, JOHN G. LUCAS, a citizen of the United States, residing at Dearborn, in the county of Wayne and State of Michigan, have invented certain new and useful Improvements in Signal-Indicators for Automobiles, of which the following is a specification, reference being had to the accompanying drawings.

10 This invention relates to new and useful improvements in automobile signals.

An important object of the invention is to provide a device of this character which operates automatically to indicate the intention 15 of the driver to stop or suddenly slacken his speed. In the operation of an automobile, in the event of some contingency requiring a sudden stop or slackening the operator of the automobile is often too busy with the 20 driving of the machine to enable him to utilize the common method of hand signaling to indicate his intention of slackening or stopping, and accordingly, unless the contingency is recognized by the driver of the 25 following automobile, a rear-end collision is very likely to occur. In addition to the automatic shifting of the signal to indicate this intention, my device likewise includes means whereby the operator may indicate 30 his intention to change his course.

A further object of the invention is to provide in a device of this character an efficient and novel operating means.

A further object of the invention is to 35 provide a device of this character extremely simple in construction, and which is composed of the minimum number of parts in order that the same may be rendered practicable for commercial exploitation.

40 Other objects and advantages of the invention will become apparent throughout the course of the following description.

In the accompanying drawings, wherein for the purpose of illustration is shown a 45 preferred embodiment of my invention, and wherein like reference characters designate like parts throughout:

Figure 1 is a diagrammatical side elevation of my signal and the connections there- 50 for:

Fig. 2 is a rear elevation of my signal;

Fig. 3 is an enlarged side elevation of the hand control;

Fig. 4 is a front elevation thereof;

55 Fig. 5 is a section on the line 5—5 of Fig. 2;

Fig. 6 is a section on the line 6—6 of Fig. 5 and,

Fig. 7 is a detail view of the foot control connections.

60

Referring now more particularly to the drawings, the signal proper consists in an outer drum 10, circular in cross section, which is provided longitudinally with a slot or opening 11. The drum is formed of sheet 65 metal and the metal at the edges of the opening 11 is crimped to afford guiding grooves 12 for the reception of the longitudinal edges of a transparent medium 13, such as 70 isinglass. The ends of the drum 14 are likewise crimped to form annular grooves 15 adapted for the reception of annular flanges 16 formed on end closure plates 17 which are provided centrally with an opening 18.

A shaft 19 is rotatably mounted in the 75 openings 18 and has secured thereto a second or inner drum 20, provided upon its periphery with a suitable insignia, preferably, the words "Go," "Right," "Left," and "Stop." The arrangement of these words is immate- 80 rial except to the extent that the word "Go" should be arranged at one end of the series and the word "Stop" at the opposite end thereof.

One end of the shaft 19, exteriorly of the 85 drum 20, is provided with a pulley 21 and with a shoulder 22. To the shoulder 22 is secured, as at 23, one end of a coil spring 24, the opposite end of the coil spring being secured to the outer casing, as at 25. Se- 90 cured to the pulley 20 and wound thereabout in a direction opposite to the direction of coil of the spring 24 is a flexible element 26 of any suitable material, such as light cable or the like. Brackets 27 may be secured to 95 the automobile in any desired manner and engage the end plates 17 of the outer drum, serving the dual purpose of preventing displacement of the end plates and supporting the signal.

100 Secured to the steering post S of the automobile immediately below the wheel, as at 28, is a casing 29 in which is rotatably mounted a drum 30. One end of the drum shaft 31 extends beyond the end wall of the 105 casing and is provided with a resilient angular extension 32, embodying an operating finger engaged portion 33. The free end of the arm 32, by reason of its resiliency, has a tendency to separate from the end wall of 110 the casing. The side wall of the casing at the end thereof upon which the angular arm

32 extends, extends beyond the end wall, as at 34, and has formed therein a slot 35 through which the arm 32 extends. This slot is provided below the upper end thereof 5 with spaced notches 36 and 37 provided with indicatory symbols to indicate various positions of the signals, as for example, L and R, for left and right. The upper end 38 of the slot provides a third positioning for the 10 arm 32 and corresponds to the positioning of the signal when the word "Go" may be seen through the opening 11 of the outer casing. The free end of the cable 26 is arranged about suitable pulleys in the conventional manner and wound about the drum 30 so that the shifting of the drum causes 15 a corresponding shifting against the action of the spring 24. It will be obvious that the arm 32, by reason of the fact that it springs 20 outwardly, will when moved past the notch engage therein and hold the signal in the adjusted position; and it will likewise be obvious that by deforming the arm, as by striking the same by the hand, the arm 32 25 will be disengaged from the notch and the arm and signal will be returned to the normal position by the spring 24.

Secured to the cable 26 in any suitable manner is a stop collar 40, arranged slightly 30 rearwardly of the cable with respect to the operating pedals of the automobile. Slidably mounted upon the cable 24, rearwardly of the stop collar 40, is a sleeve 41 to which is secured one end of the spring 42, the 35 opposite end of which is secured, as at 43, to the brake pedal 44 at a point spaced from the pivot pedal thereof. It will be obvious that upon application of the brake, the motion thereof will be transmitted to the cable 40 24 shifting the same and causing the word "Stop" to appear in the opening 11. To limit the rotation of the inner rotatable drum, I have provided upon one of the heads 17 of the outer drum, an inwardly projecting radial flange 45, and upon the end of the inner rotatable drum an outwardly projecting portion 46 which is adapted to come into engagement with the flange when the word "Stop" is alined with the opening 50 11. This provision is necessary, as is the spring 42, by reason of the fact that the brake pedal due to wearing of the brake bands in use does not move a uniform distance at all times and the change in distance 55 must be compensated to prevent breakage. The spring 42 will, of course, be strong enough to overcome the motion of the coil spring 24, but will not be of sufficient strength to place a dangerous strain upon 60 the cable 26.

It will be obvious that my device, by reason of the simplicity of its construction and the ease with which it may be operated, is particularly well adapted for the use for 65 which it is intended; and it will likewise be

obvious that the construction of the same as hereinbefore set forth is capable of some change without in any manner departing from the spirit of my invention. I, accordingly, do not limit myself to such specific 70 structure, except as so limited by the subjoined claims.

What I claim is:

1. In an automobile signal, an outer casing comprising a tubular sheet metal portion provided with a longitudinal slot, the metal at the edges of said slot being crimped to afford guide grooves, a transparent medium closing said slot and having its longitudinal edges disposed within said guide 75 grooves, the ends of said tubular member being likewise crimped to form an annular groove, end plates for said casing embodying an annular flange adapted to engage in said annular grooves and a drum rotatably mounted within said casing provided upon the exterior thereof with indicatory symbols alinable with the slot of said casing.

2. In an automobile signal, an outer casing comprising a tubular sheet metal portion provided with a longitudinal slot, the metal at the edges of said slot being crimped to afford guide grooves, a transparent medium closing said slot and having its longitudinal edges disposed within said guide 80 grooves, the ends of said tubular member being likewise crimped to form an annular groove, end plates for said casing embodying an annular flange adapted to engage in said 85 annular grooves and a drum rotatably mounted within said casing provided upon the exterior thereof with indicatory symbols alinable with the slot of said casing.

3. In an automobile signal, an outer casing comprising a tubular sheet metal portion provided with a longitudinal slot, the 90 metal at the edges of said slot being crimped to afford guide grooves, a transparent medium closing said slot and having its longitudinal edges disposed within said guide 95 grooves, the ends of said tubular member being likewise crimped to form an annular groove, end plates for said casing embodying an annular flange adapted to engage in said annular grooves and a drum rotatably 100 mounted within said casing provided upon the exterior thereof with indicatory symbols alinable with the slot of said casing, said end plates being provided with openings, said inner rotatable drum embodying 105 a supporting shaft rotatably mounted in said openings.

3. In an automobile signal, an outer casing comprising a tubular sheet metal portion provided with a longitudinal slot, the 110 metal at the edges of said slot being crimped to afford guide grooves, a transparent medium closing said slot and having its longitudinal edges disposed within said guide 115 grooves, the ends of said tubular member being likewise crimped to form an annular groove, and plate for said casing embodying an annular flange adapted to engage in said annular grooves and a drum rotatably mounted within said casing provided upon 120 the exterior thereof with indicatory symbols alinable with the slot of said casing, said end plates being provided with openings, said inner rotatable drum embodying a supporting shaft rotatably mounted in said 125 openings, said shaft being held against rotation with relation to said drum, a spring having one end secured to said shaft and wound thereabout and the opposite end thereof secured to said casing and tending 130

to rotate said drum in one direction, a pulley mounted upon said shaft, a flexible element wound about said pulley in a direction opposite to the direction of rotation imparted to the drum by said spring whereby longitudinal shifting of said flexible element in a direction tending to unwind the same from said shaft will cause reverse rotation of said drum and coacting means carried by said 10 drum and said casing for limiting the amount of such reverse rotation.

4. In an automobile signal, an outer casing comprising a tubular sheet metal portion provided with a longitudinal slot, the 15 metal at the edges of said slot being crimped to afford guide grooves, a transparent medium closing said slot and having its longitudinal edges disposed within said guide

grooves, the ends of said tubular member being crimped to form an annular groove, 20 end plates for said casing embodying an annular flange adapted to engage in said annular grooves and a drum rotatably mounted within said casing provided upon the exterior thereof with indicatory symbols alinable with the slot of said casing, said end plates being provided with openings, said inner rotatable drum embodying a supporting shaft rotatably mounted in said openings, brackets secured to said end plates and 30 to the automobile supporting said casing and drum and preventing displacement of said end plates.

In testimony whereof I hereunto affix my signature.

JOHN G. LUCAS.
